VENTING VALVE SYSTEM FOR NIPPLES

Yervant H. Kurkjian, Paterson, N. J.

Application February 21, 1934, Serial No. 712,424

8 Claims. (Cl. 128—252)

This invention relates to nipples, and has for one of its objects the production of a simple and efficient nipple which is especially designed for use in connection with wide-mouthed nursing bottles.

Another object of this invention is the provision of a simple and efficient means for attaching a flexible nipple to a wide-mouthed nursing bottle in such a manner as to provide means for controlling the entrance of air into the interior of the bottle and at the same time prevent the leakage of liquid from a bottle as soon as suction is released from the nipple.

A further object of this invention is the provision of a simple and efficient nipple having vent means formed therein, the nipple being so constructed as to permit the entrance of air through the vent means into the interior of the bottle upon which the nipple is mounted and while suction is being applied to the nipple, and at the same time permit the vent means to automatically close as soon as suction is released from the nipple.

A still further object of this invention is the provision of a simple and efficient nipple which may be inverted to extend into the nursing bottle when not in use, the nipple being associated with means for facilitating the sealing of the open end of the bottle and provide a sanitary protection of the nipple.

Other objects and advantages of the present invention will be apparent throughout the following specification and claims.

In the drawings—

Figure 1 is a side elevation partly in section of the improved nipple;

Figure 2 is a section taken on line 2—2 of Figure 1;

Figure 3 is an enlarged fragmentary side elevation of the nipple showing the manner in which the same is secured upon a bottle in conjunction with the securing cap;

Figure 4 is a vertical sectional view of a modified form of the invention illustrating the manner in which the nipple is mounted upon a wide-mouthed bottle and also showing the retaining cap associated with the nipple and bottle;

Figure 5 is a perspective view of the nipple shown in Figure 4, a certain portion thereof being shown in section;

Figure 6 is a vertical sectional view through a further modified form of the nipple showing the nipple in position upon a wide-mouthed bottle and illustrating the retaining cap or securing cap in position;

Figure 7 is a vertical section through the open end of a bottle showing the nipple sealing disc and securing cap in position for holding the nipple in a sanitary sealed position within the outer end of the bottle when the nipple is not in use;

Figure 8 is a perspective view of the sealing disc;

Figure 9 is a vertical sectional view through the open end of a wide-mouthed bottle illustrating a modified type of sealing disc or plug which may be used in conjunction with the nipple;

Figure 10 is a perspective view of the sealing plug or disc illustrated in Figure 9; and

Figure 11 is a side elevation partly in section of a further modified form of the nipple.

By referring to the drawings, it will be seen that 1 designates the bottle which is preferably of the wide-mouthed type, having the usual threaded portion formed at its outer end, as illustrated. A threaded cap 2 is adapted to be threaded upon the threaded neck of the bottle 1, as shown in Figure 3, and this cap 2 is provided with a centrally located aperture 2a, the aperture 2a being surrounded by means of an upstanding annular flange 2b.

In conjunction with this threaded cap 2, I provide a specially constructed nipple 3 which nipple 3 is provided with an outwardly extending annular flange 4 which flange 4 is provided with a thickened outer edge or periphery 4a, the flange being normally flat upon its upper face 4b, upon which upper face 4b is arranged an annular bead 4c, which bead is connected to the upper face 4b by means of a restricted neck portion 4d, as shown in Figure 1. The annular bead 4c is preferably located at a point intermediate the inner and outer edges of the flange 4, as shown in Figure 1. The under face of the flange 4 is provided with a circumferentially extending annular concave channel 4e to provide a relatively thin portion 4f at a point between the neck portion of the nipple 3 and the annular bead 4c to increase the flexibility of the flange 4 at this point. The nipple 3 is provided with a thickened heel portion 5 at the junction of the flange 4 with the neck of the nipple, as shown in Figure 1 to efficiently reinforce the nipple at this point and provide means for decreasing the possibility of the collapsing of the nipple. The flange 4 is provided with a series of vents 6 preferably of small dimension at properly spaced distances, and arranged circumferentially between the bead 4c and the outer thickened portion 4a of the flange 4.

Additional vent openings 7 may also be formed 55

in the neck of the nipple 3 at a point which would normally be located below the upper edge of the annular flange 2b of the retaining cap 2, the inner wall 2c of the flange 2b normally fitting 5 snugly against the side wall of the neck 3 of the nipple to close the vents 7. When a partial vacuum is created in the bottle by suction, external air pressure will cause walls of the nipple to collapse and flex inwardly and downwardly away 10 from the upper edge and inner face of the flange 2b to uncover the vents 7 and permit entrance of air into the nipple and if sufficient vacuum is created collapsing of the nipple will continue until the bead 4c flexes away from the inner face 15 2d of the retaining cap 2 thereby permitting the entrance of air through the vents 6. After sufficient air has entered the bottle through the vents the nipple will expand and return to its extended condition.

20 It should be understood that the body of the nipple, as well as the flange, is preferably formed of rubber or other similar elastic or resilient material.

By carefully considering Figure 3, it will be 25 seen that when the nipple is attached to the bottle the retaining cap 2 is placed in the position shown in Figure 3, the thickened portion 4a of the flange 4 will be firmly clamped between the inner face 2d of the cap 2 and the upper end 8 30 of the bottle 1, thereby firmly holding the flange against accidental displacement. The upper edge of the bead 4c which is preferably circular in cross-section will normally contact with the under face 2d of the cap 2 and because of the 35 resilient nature of the flange 4 and the resilient nature of the nipple 3, this annular bead 4c will be firmly held in contact with the inner face 2d of the cap 2 until a sufficient suction or vacuum is created in the bottle to permit external air 40 pressure to cause the bead 4c to flex away from the cap 2, and the neck of the nipple 3 to flex away from the flange 2b at which time air may pass between the neck of the nipple and the flange 2b and under the cap 2 and over the bead 45 4c and through the vent opening 6. Air may also pass through the vent opening 7 and if desired the vent opening 7 may be eliminated without departing from the spirit of the invention. As soon as the vacuum has been relieved the parts 50 will immediately return to their sealing position such as is shown in Figure 3, and prevent the accidental leakage of liquid through the nipple. It should be understood that the relatively thin portion 4f will constitute an efficient means to 55 permit the parts to properly flex and to provide a proper sealing action. The annular bead 4c will constitute an efficient valve means for controlling the flow of air into the bottle through the vent opening 6.

60 By considering Figures 4 and 5 of the drawings which show a modified form of the invention, it will be seen that 10 designates the bottle which is preferably of the wide-mouth type having the usual threaded portion 11 at its outer end. A 65 threaded cap 12 is adapted to be threaded upon the threaded portion 11, as shown in Figure 4, and this cap 12 is preferably provided with a centrally located aperture 13 around which extends a tapering annular flange 14, also shown in Figure 4.

In conjunction with the bottle 10 and the cap 12, I employ a specially constructed nipple 15 which is provided with an annular flange 16 around its inner end, the nipple 15 having at its 75 junction with the flange 16 a thickened stock or

heel portion 17 which is adapted to normally extend slightly below the outer edge 18 of the flange 16, as shown clearly in Figure 4. This thickened stock or heel portion 17 will constitute an efficient reinforcing means for the nipple at its inner end 5 and at its point of junction with the flange 16 and will tend to prevent the collapsing of the nipple or the falling of the nipple 15 into the interior of the bottle 10. The flange 16 preferably tapers from the thickened heel portion 17 of the nipple 10 toward its outer edge 18, as shown in Figure 4, and the flange 16 is preferably arranged to normally extend in transverse section in concavo-convex formation, as shown in Figure 4. This position of the flange 16 will normally force the 15 upper face 19 of the flange 16 into contact with the lower face 20 of the cap 12, at a point substantially its circumferential center and a plurality of vent openings 21 are formed through the flange 16 intermediate the outer and inner edges 20 of the flange, and at a point to cause the vent openings 21 to be normally closed when the flange 16 contacts with the under face 20 of the cap 12. Additional vent openings 22 may also be formed in the side walls of the nipple 15, as shown in Figure 4, at a point within the height of the flange 14 so as to cause the vent openings 22 to normally remain close by the inner face of the flange 14 when the side walls of the nipple 15 contact with the inner face of the flange 14 under normal 30 conditions.

When the nipple 15 is being used, the suction or vacuum created within the nipple 15 will permit air pressure externally of the bottle to cause the side walls of the nipple 15 to flex inwardly 35 away from the flange 14 and the flange 16 to flex away from the cap 12 to the position shown in dotted lines in Figure 4, thereby permitting the entrance of air in between the flange 14 and the neck of the nipple 15 whereupon the air will pass 40 through the vents 21 and 22 in the direction indicated by the arrow and permit an even flow of milk or other liquid through the nipple 15. As soon as sufficient air has entered the bottle, the resilient nature of the body of the nipple will 45 cause the flange 16 to immediately contact with the under face 20 of the cap 12 at a point adjacent the vent openings 21 thereby sealing these openings and the neck of the nipple 15 will also immediately contact with the inner face of the 50 flange 14 thereby sealing the vent openings 22 and prevent the accidental flow of liquid out through the sucking opening 23 formed in the outer end of the nipple 15. As shown in Figure 4, only the outer edge of the flange 16 rests upon 55 the outer edge 24 of the bottle 10 and this will constitute an efficient means for holding the nipple flange in position in conjunction with the cap 12 and at the same time permit the flange 16 to properly flex inwardly to permit the entrance of 60 air and to immediately return to a sealing position as soon as the infant using the nipple discontinues the sucking upon the nipple or releases the suction from the nipple.

It will, therefore, be seen that a very simple and 65 efficient automatic valve controlling means has been provided formed directly within the nipple itself for permitting an even flow of liquid out through the nipple when the nipple is in use and at the same time immediately seal the vent openings when suction is released from the nipple to prevent accidental leakage or flow of liquid from the nipple.

Figure 4 illustrates the structure above described in an exaggerated manner, in order to 75

clearly bring out the arc-shaped formation of the flange in cross-section which greatly facilitates the forcing of the flange adjacent the vent openings in sealing contact with the under face 5 of the cap 12.

In Figure 6, I have shown another modified form of the invention wherein the bottle is indicated by the numeral 25 and is provided with the usual threaded end 26 upon which fits a threaded 10 cap 27, the threaded cap having a centrally located aperture 28 through which the neck 29 of the nipple extends. In this form of the invention, the nipple 30 is provided with the laterally extending annular flange 31, the edge of the flange 15 being adapted to be firmly clamped between the under face of the cap 27 and the upper or outer edge of the bottle 25. The flange 31 is provided with a plurality of vent openings 32 which are arranged in any suitable or desired number, 20 through the flange 31 preferably at a point intermediate the inner and outer marginal edges of the flange 31. The flange 31 is adapted to normally lie flat in contact with the under face of the cap 27 and the aperture 28 in the cap 27 is 25 of sufficient size to permit air to pass between the neck 29 of the nipple 30 and the side wall of the aperture 28 when the flange 31 is flexed inwardly by external air pressure when a partial vacuum is formed in the bottle. As an infant 30 sucks upon the nipple 30, and air is drawn out of the bottle to form a partial vacuum therein the external air pressure will cause the flange 31 to flex inwardly and pull the flange 31 slightly away from the cap 27 and thereby permit the passage 35 of air through the aperture 28 under the cap 27 and through the vent openings 32 formed in the flange 31 into the bottle. As soon as sufficient air has entered the bottle, the flange 31 will immediately snap back to a sealing position in 40 contact with the under face of the cap 27 and close the vent openings 32 against the entrance of air and thereby prevent the flow of liquid out through the nipple.

In conjunction with the nipple, I may also employ a sealing disc 32 which may be used when carrying a nursing bottle filled with liquid to be used at a later time. In this event, the nipple 30 may be inverted to the position shown in Figure 7, and the sealing disc 32 may be placed over 45 the flange 31 so as to completely cover the same. The disc 32 is preferably provided with a circular lug 33 which is adapted to snugly fit within the aperture 28 of the cap 27 and normally lie flush with the outer face of the cap thereby completely sealing the outer end of the bottle and protecting the nipple in a completely sanitary manner. This disc 32 will constitute an efficient sealing means in conjunction with the threaded 50 cap 27, as shown in Figure 7.

As shown in Figures 9 and 10, I may employ a modified form of a sealing member 34. In using 55 this sealing member 34, the nipple is inverted within the bottle so as to have the flange 31 overhang the outer end of the bottle and the threaded cap 27 is threaded in position to clamp the nipple 30 upon the end of the bottle in an inverted position. The sealing member 34 is then placed upon the cap 27, and this sealing member 34 comprises preferably a circular disc 60 completely covering the outer end of the cap 27. This disc is indicated by the numeral 35 and is provided with a tapering plug 36 which is adapted to extend through the aperture 28 of the cap 27 and into the neck 29 of the nipple 30. The re- 65 siliency of the nipple will assist in holding the

plug 36 in a firmly clamped position. A knob 37 is carried by the outer face of the disc 35 for facilitating the handling of the sealing member 34, that is to say, the placing of the sealing member in position or the removal of the sealing member. 5

In Figure 11, I have shown a further modified form of the improved nipple wherein 40 designates the body of the nipple, the nipple having an annular flat flange 41 which is provided with vent openings 42. The body is thickened, as at 43, adjacent the inner end of the nipple adjoining the flange 41 and this thickened portion projects slightly below the lower face of the flange 41 to provide a thickened reinforcing annular 15 bead 44. 10

It should also be understood that certain detail changes in the construction may be employed without departing from the spirit of the invention, so long as such changes fall within the 20 scope of the appended claims.

Having described the invention, what is claimed as new is:—

1. In combination with a bottle having an open outer end, a removable retaining cap having an 25 annular bead overhanging the outer end of the bottle, a nipple having a laterally extending retaining flange adapted to be clamped between the bead of the cap and the mouth of the bottle, the flange being of flexible elastic material and having 30 vent openings formed therein normally closed at their outer ends by the bead, and said nipple being thickened adjacent its lower end, the thickened portion projecting slightly below the lower end 35 of the nipple to provide a reinforcing annular bead. 5

2. In combination with a bottle having an open outer end, a cap removably connected with the open end of the bottle, an elastic nipple having a laterally extending flange adapted to be clamped 40 between the cap and the bottle, the flange having vent openings formed therein normally covered at their outer ends by the cap and the body portion of the nipple extending outwardly through the retaining cap. 45

3. In combination with a flexible nipple having a flexible laterally extending portion, the flexible laterally extending portion being relatively thin at a point adjacent the neck portion to facilitate the flexing of the laterally extending portion, said laterally extending portion having vents formed therethrough, the vents being located beyond the relatively thin portion, a rigid cap having an inwardly extending overhanging flange adapted to contact with said laterally extending portion of the nipple and to bind said laterally extending portion upon the neck of a bottle, the laterally extending portion of the nipple within which the ventilating apertures are formed being free to flex away from the flange of said cap 50 whereby external atmospheric pressure will force said laterally extending portion out of contact with the underface of said flange when a vacuum is created below the flange to permit the entrance of air through the ventilating apertures. 55

4. The combination with a bottle having an open outer end, a rigid cap fitted upon the outer end of said bottle and having an inwardly extending rigid flange, of a flexible nipple having a flexible neck and a flexible laterally extending portion adapted to fit between said flange and the outer end of said bottle and adapted to be clamped in position upon the bottle by said flange, said flexible laterally extending portion of said nipple being reduced in thickness to pro- 70 75

vide a thin portion at a point near said neck to facilitate the flexing of said laterally extending portion, said laterally extending portion having venting apertures formed therein and located between the outer end of the bottle and the thin portion of the laterally extending portion of the nipple whereby the laterally extending portion of the nipple surrounding the venting apertures will normally contact with the under face of said cap, the laterally extending portion of the nipple being adapted to flex away from the under face of the flange of the said cap when a vacuum is created within the bottle caused by sucking upon the nipple, the laterally extending flexible portion of the nipple being movable away from the under face of the flange of the cap by external atmospheric pressure upon the flexible nipple to permit the entrance of air through the venting apertures and into the bottle, said flexible portion being adapted to automatically contact with the underface of the flange of the cap when the air pressure within the bottle equalizes the external air pressure to prevent leaking of the nipple.

25 5. In combination with a bottle, a retaining cap removably secured to said bottle, a flexible nipple extending through said cap and having an outwardly projecting elastic flange provided with a thickened portion near its outer extremity to provide a retaining means for clamping the flange in position between the cap and the end of a bottle, said flange having vent openings therein, and an annular sealing bead carried by and rising from said flange between the vent openings and the nipple adapted to move into and out of contact with the under face of said cap and constitute a barrier for normally preventing passage of air through said vent openings but movable away from the cap as the internal air pressure is varied relative to the external air pressure, thereby permitting the entrance of external air between said nipple and cap under the cap and through the vent openings into said bottle.

6. In combination with a bottle, a retaining cap removably and adjustably secured to said bottle, a flexible nipple of elastic material extending through said cap, said flexible nipple having a body and an outwardly projecting flange about the base of the body provided with a thickened portion near its outer margin to provide a retaining means for clamping the flange in position between the cap and the end of a bottle, said flange having vent openings therein, an annular upstanding sealing bead carried by said flange intermediate the vent openings and inner margin of the flange adapted to move into and out of contact with the under face of said cap and when in engagement with the cap constituting a barrier for preventing inward passage of air through said vent openings, said bead having a narrow neck portion at the point of junction with said flange, and said flange being reduced in thickness adjacent said sealing bead to facilitate the flexing of the flange and the movement of the bead away from said cap as

the internal air pressure is varied relative to the external air pressure thereby permitting the entrance of external air pressure between the nipple and cap under the cap and through the vent openings into said bottle.

7. The combination with a securing cap adapted to secure a flexible nipple to the neck of a wide-mouthed bottle, of a nipple having a neck and a laterally extending flange formed of flexible elastic material, the flange having minute ventilating apertures arranged in lateral spaced relation with respect to said neck, said cap having an aperture through which said neck of the nipple extends, the ventilating apertures in the said flange being arranged in spaced relation in a radius greater than the radius of the aperture formed in the cap, the aperture formed in the cap being of greater diameter than the diameter of the neck of the nipple whereby the nipple may be passed through the cap, said flange engaging the under face of said cap and normally contacting therewith to seal said ventilating apertures and being adapted to flex away from said cap through the medium of the external air pressure when a vacuum is created within a bottle to which the nipple is attached to permit the inrush of air through said apertures and also cause the flange to immediately and automatically return to a sealing position as soon as suction is released from the nipple, said flange having a bead formed thereon adapted to engage the cap to control the passage of air through said ventilating apertures, said cap having means for receiving the flange, and the flange being adapted to be clamped into position between said cap and the end of the bottle.

8. In combination with a bottle, a cap adapted to be removably secured upon the outer end of the bottle, a flexible nipple of material having a neck portion and a laterally extending annular flange, the flange being adapted to be clamped between the cap and the end of the bottle for holding the nipple in position, the cap having a central aperture, the cap also having an outwardly extending annular flange extending around the aperture formed in the cap, the neck portion of said nipple having vents formed therein, the neck of the nipple being normally disposed in close contacting engagement with the inner face of said flange whereby the flange serves for normally closing said vents, other vents being formed in said flange of the nipple and normally closed at their outer ends by engagement of the outer face of the nipple flange with the inner face of the cap, the neck and flange of the nipple being adapted to flex away from the outwardly extending annular flange and the cap through the medium of external air pressure when a vacuum is built up within the bottle whereby external air pressure will pass between the neck of the nipple and inner face of the flange of said cap, under said flange, through said vents and into said bottle.
